UNITED STATES PATENT OFFICE

HORACE W. PERRY, OF OAK PARK, ILLINOIS, ASSIGNOR TO RELIABLE ELECTRIC COMPANY, OF CHICAGO, ILLINOIS, A CORPORATION OF ILLINOIS

WIRE CLAMP

Application filed June 8, 1931. Serial No. 542,876.

My invention relates to improvements in clamps for securing flexible members and more particularly to means for securing electrical conductors and wires to supports.

5 One of the objects of my invention is to provide a clamp of this character to fasten conductors or other flexible strands to supports with a minimum expenditure of time and labor and without the use of auxiliary 10 wedges and the like.

It is also a purpose of my invention to provide a clamp of this character in which the conductor or other strand or strands may be secured to the clamping member in such 15 fashion that the ends thereof will be substantially aligned although a straight pull thereon will simply tighten the clamping action of the clamp member.

More specifically it is a purpose of my 20 invention to provide a clamping member which in and of itself is capable of securely holding the strand or strands and to provide a mounting member therefor by means of which the clamping member may be mounted 25 in place.

My invention contemplates also a clamp of this character in which the clamping portion of the device can be made smooth so as not to have a tendency to destroy the 30 insulation or other covering of the conductors.

My invention is equally applicable to a single strand, a plurality of parallel strands, or twisted strands.

I will describe one form which my invention 35 may take by reference to the accompanying drawing wherein—

Fig. 1 is a plan view partly in section of the clamping device;

Fig. 2 is a longitudinal section through 40 the clamping device;

Fig. 3 is a transverse section on the line 3—3 of Fig. 2;

Fig. 4 is a perspective view of the clamping member; and

Fig. 5 is a side view partly in section of a slightly modified form of clamping member.

Referring now in detail to the drawing, the clamping device consists of two elements, a clamping member 6 and a holder 7. The holder 7 is preferably bent into a transverse

U-shaped structure and may be made of any suitable sheet material. The extension 8 of the holder forms a means for mounting the device upon a support and is apertured as indicated at 9 for this purpose. The clamping 55 member 6 is also transversely U-shaped and is adapted to slide in from the large end of the holder 7. The holder and the clamping member are tapered so that they will wedge together as shown clearly by Figs. 2 and 4. 60 The member 7, as shown, has the top edges 10 and 11 bent over and turned down so as to form guideways or tracks for the side walls of the member 6. The shape of the member 6 forms a trough or groove extending in from both ends so that the wire 12 or other flexible strand or strands enters and leaves the clamping member in substantially a straight line. The clamping member, however, intermediate its ends is provided with 70 a groove 13 which extends across the back of the member and enters the central trough through the opposite side walls of the members 6 at the openings or slots 14 and 15. The edges of the slots are preferably slightly 75 rounded or smoothed off so they will have no tendency to cut the covering of the wire inserted.

The substantially complete encircling of the clamping member by the flexible strands 80 gives a sufficient frictional grip between them to prevent any sliding, and the groove 13 may be made perfectly smooth because of this factor although, of course, if it is desired to roughen it, the function would remain much 85 the same. The advantage of this smooth groove lies in the fact that there is less tendency to injure the covering of electrical conductors.

The assembling of the wire with the clamping device is made very simple by this construction. The clamping member 6 when free of the holder 7 can be held in the hand and the wire 12 quickly laid therein in the position shown in Fig. 1 where it will retain 95 the wire without any holding by any auxiliary means. The holder 7 is then shoved on to the clamping member and mounted upon the support.

A principal function of the holder 7 is to 100

serve as a holding and mounting means for the clamping member and to serve as a protection for the groove 13. The holding member does aid, however, in holding the wire 5 in the groove, for example in the case where the wire may be slightly too large to fit properly in the groove. There is little likelihood of the conductors becoming displaced from the groove whether or not the holder is placed 10 thereon since any pressure or pull applied on the conductors thereof merely tends to draw the conductors tighter in the groove.

In Fig. 5 a slightly modified form of the 15 invention is shown. The structures in Figs. 1-4 show the clamping member 6 as being constructed of an insulating material such for example as phenolic resin compound known as bakelite. The structure in Fig. 5 has the same conformation, but the clamping 20 member here is shown of sheet metal with the groove 13' thereof formed by pressing the groove upwardly in the material.

From the above description, it is believed 25 that the construction and advantages of this device will be clear to those skilled in the art. It is also believed to be obvious that the invention is not limited to the exact details shown and described but that the structure may be varied as to details without falling 30 outside the scope of the invention.

Having thus described my invention, what I claim as new and desire to secure by Letters Patent is:

1. A clamp comprising an elongated transversely U-shaped clamping member having a groove extending around the back of said member and opening through the opposite side walls thereof to the space between said walls and means for mounting said member on a support.
2. A clamp comprising an elongated transversely U-shaped clamping member having a groove extending around the back of said member and opening through the opposite side walls thereof to the space between said walls and means for mounting said member on a support, said means comprising an elongated transversely U-shaped holder having mounting means thereon.
3. A clamp comprising an elongated transversely U-shaped clamping member having a groove extending around the back of said member and opening through the opposite side walls thereof to the space between said walls and means for mounting said member on a support, said means comprising an elongated transversely U-shaped holder having mounting means thereon, said holder and clamping member being tapered toward one end so the clamping member may be wedged into said holder.
4. A clamp comprising an elongated transversely U-shaped clamping member having a groove extending around the back of said member and opening through the opposite

side walls thereof to the space between said walls and means for mounting said member on a support, said means comprising an elongated transversely U-shaped holder having an extension at one end thereof for mounting 70 the clamping member.

In witness whereof, I hereunto subscribe my name this 16th day of May, A. D. 1931.

HORACE WM. PERRY.
